UNITED STATES PATENT OFFICE.

CHARLES V. ALQUIST, OF NORWICH, CONNECTICUT.

GRINDING MACHINE.

1,402,704.

Specification of Letters Patent. Patented Jan. 3, 1922.

Application filed November 2, 1920. Serial No. 421,230.

To all whom it may concern:

Be it known that I, CHARLES V. ALQUIST, a citizen of the United States, residing at Norwich, in the county of New London and 5 State of Connecticut, have invented new and useful Improvements in a Grinding Machine, of which the following is a specification.

This invention relates to grinding machines of the class wherein provision is made 10 for grinding two sides of an object simultaneously, and has for one of its objects to improve and simplify the construction and increase the efficiency and utility of devices 15 of this character.

Another object of the invention is to provide a device of this character which may be attached without material structural change, to planers and like machines of 20 various forms and sizes.

With these and other objects in view, the invention consists in certain novel features of construction as hereinafter shown and described and then specifically pointed out 25 in the claim, and in the drawings illustrative of the preferred embodiment of the invention.

Figure 1 is a side elevation of a portion of a conventional planer with the improvements applied.

Fig. 2 is a plan view.

Fig. 3 is a front elevation, and

Fig. 4 is a rear elevation, of the parts shown in Fig. 1.

Fig. 5 is an enlarged vertical section of the head portion of the improved device.

Fig. 6 is a section on the line 6-6 of Fig. 5.

Fig. 7 is an enlarged section of the idler 40 housing, on the line 7-7 of Fig. 2.

Fig. 8 is an enlarged section on the line 8-8 of Fig. 1.

The improved device is designed more particularly for expediting the finishing of

45 the splines or grooves in broaches and like grinding or reaming tools, but is not necessarily limited to this specific object, and it is not desired to limit the invention in this respect.

50 For the purpose of illustration, the improved device is shown applied to a conventional planer, in which 10 represents the

bed, 11 the side frames and 12 the transverse head support, of the usual construction.

55

Attached to or integral with the head member 12 is a vertical plate 14 having dovetailed edges to slidably receive another plate 15, the latter being adjustable vertically on the member 14 by a vertical screw 60 indicated at 16, and provided with a turning head 17.

Attached as by cap screws 18 to the plate 15 is a hanger member 19 having lateral extensions 20, the latter having bearing lugs 65 21 at the ends to receive an adjusting screw 22 rotatable by a hand wheel 23.

The member 19 together with its extensions 20 is formed with a continuous dovetailed rib 24 on which bracket devices 25 70 having dovetailed sockets are slidably disposed.

Each of the brackets 25 is provided with a threaded lug 26 in which the screw 22 operates, the screw having right and left 75 handed threads, so that as the screw is rotated by its hand wheel 23, the brackets 25 will be adjusted toward or away from each other according as the screw is rotated to the right or left.

At its lower ends each bracket 25 is formed with bearings 27 to rotatively receive a tubular journal 28 extending from a tubular head member 29. The head member 29 is longitudinally and transversely 85 bored, the longitudinal bore formed with intermediate stop shoulders 30, and the transverse bore communicating with the bore of the journal 28.

Bearing respectively upon the shoulders 90 30 are supporting sleeves 31, and fitting within the longitudinal bore adjacent the outer ends of the sleeves 31 are bearing rings 32 for bearing balls 33, the rings coacting with similar and reversely disposed bearing rings 34.

The head member 29 is provided with shaft supporting devices, and extending through these devices and likewise through the head member 29 is a spindle 35. A 100 collar 36 surrounds the spindle at its upper end, the latter reduced at the lower end to form a seat for a bearing ring 34.

The upper end of the spindle 35 is thread-

ed to receive a take up nut 37, the latter split and provided with a clamp bolt 38 to enable the nut to be rigidly coupled to the spindle in adjusted position.

5 Bearing upon the head member 29 at its upper and lower ends are bearing collars 39 and 40, the collar 39 is reduced to bear upon the ring member 32, and internally threaded to receive a covering cap 41.

10 At its upper end the sleeve 31 is reduced to form a seat to engage in an annular recess in the lower face of the collar 36.

The holding collars 39 and 40 are retained in position respectively by cap screws 42 and 43.

15 Disposed within the longitudinal bore of the member 29 at its lower end is a bearing ring 44 for bearing balls 45, the ring 44 co-acting with a similar bearing ring 46, as shown.

20 Mounted on the spindle 35 is a sleeve 47 having an annular lip 48 at the lower end to support the inner bearing ring 46.

The bearing collar 40 is formed with an 25 upwardly directed flange 49 to engage in a seat in the sleeve 47, as shown in Fig. 5.

The spindle 35 is formed with a stop shoulder 50 to support the sleeve 47, and is likewise provided with an integral stop col-

30 lar 51 spaced from its lower end with the part of the spindle in advance of the latter collar threaded to receive the abrading element, for instance a grinding wheel 52 of emery or the like and held in position on the 35 spindle by lock nuts 53.

Attached in any suitable manner to the head member 29 is a cover plate 54, to close the transverse bore.

40 Mounted on the spindle 35 within the transverse bore of the head member 29 and between the sleeves 31 and 47, is a belt pulley 55, being preferably locked from movement on the spindle as by a clamp screw 56.

45 The pulley 55 is formed with annular channels in its upper and lower faces to receive packing rings 57, of felt or the like.

50 Attached to the rear faces of the sides 11 of the planer frame are brackets 58, and supported in each bracket is a stud 59. Sup- 55 ported upon the outer end of each stud is a rearwardly opening yoke 60. Disposed within each yoke is a bearing collar 61, and held from turning in the yokes by combined centering and supporting screws 62. A drive shaft 63 is mounted for rotation through the collars 61 and is provided with a loose belt pulley 64 and a tight belt pulley 65.

60 Extending from each of the yokes 60 is an arm 66 through which a belt shifter rod 67 is slidably disposed, the rod having a fork member 68 to engage the drive belt 69. By this means the motion of the belt 69 may be imparted to the shaft 63, or disconnected therefrom as will be obvious.

Formed through each side member 11 of 65 the frame is an opening, one of which is represented at 70 in Fig. 8, each opening being surrounded by an outwardly directed flange 71, and bearing upon each flange and over the opening is a closure disk 72.

70 Disposed internally of the frame sides 11 and extending over the openings 70 are other disks, one of which is shown at 73 in Fig. 8, and provided with stop lugs 74 each having a seat to engage the adjacent inner edge of 75 the opening 70. Clamp bolts 75 are passed through the two disks 71 and 72 and bind them firmly in position upon the frame sides 11, while at the same time the disks may be adjusted rotatably by loosening the clamp 80 bolts 75, as will be obvious.

Each of the disks 73 is provided with a bearing, one of which is shown at 76, to receive a shaft 77.

85 Mounted to swing upon the shaft 77 are housing members each including vertical spaced sides 78 and a connecting top member 79. A shaft 80 is supported at its ends in the side portions 78, and mounted for rotation upon each shaft between the spaced 90 sides is an idler roller 81, preferably with roller bearings 82, as shown, to reduce the friction.

95 Mounted on the shaft 63 is a relatively long drum or belt pulley 82, and extending 100 respectively around the drum 82 and around the small belt pulleys 55 on the spindles 35, are drive belts 83, the belts being necessarily given a half twist in passing from the horizontally mounted drum 82 to the vertically mounted pulleys 55.

105 In passing beneath the idler pulleys 81, the latter operate to hold the belts together so that they pass without friction through the contracted spaces within the tubular journals 28 and heads 29.

110 By this means two distinct and separate grooves or splines may be simultaneously operated from opposite sides, for instance from opposite sides of a broach or like cutting tool or implement, and the cutting elements and the element being acted on held in exact and true position, so that the splines will be exactly alike on each side. Moreover 115 the abrading or cutting disks 52 operating with equal force at opposite sides of the element being acted on, hold the work steadily in position and prevent lateral displacement or lateral strains.

120 I claim:

125 In an apparatus of the class described, a supporting frame including a vertical face member, a supporting member attached to said face member and having vertical guideways, a bracket device adjustably engaging said guideways, and having lateral extensions, coating brackets slidably on said extensions, a tubular head for each of said

brackets and each having a tubular bearing engaged respectively by the brackets, means for adjusting said brackets toward and away from each other, a spindle for an abrading element mounted for rotation in each of said tubular heads, a belt pulley carried by said spindle within said head, a drive shaft

mounted on said support and carrying a belt pulley, and a drive belt operating through each of said tubular bearings and around 10 said pulleys.

In testimony whereof, I affix my signature hereto.

CHARLES V. ALQUIST.
